UNITED STATES PATENT OFFICE

2,067,245

GAME APPARATUS

David C. Rockola, Chicago, Ill., assignor to Rock-Ola Manufacturing Corporation, Chicago, Ill., a corporation of Illinois

Application January 6, 1936, Serial No. 57,645

4 Claims. (Cl. 273—121)

This invention relates to game apparatuses.

It is an object of this invention to provide an improved game apparatus which is relatively simple and inexpensive in construction and efficient in use.

Another object of the present invention is to provide a novel game apparatus of the pin and marble game type embodying a cabinet including a member providing a ball-playing surface provided with ball-receiving pockets, ball-stopping members movably mounted upon or above the playing surface of the cabinet and adapted, when in effective position, to prevent balls from entering the ball-receiving pockets with which the ball-stopping members are associated.

A further object of the invention is to provide a novel device for moving the aforesaid ball-stopping members into ineffective or raised position so that balls traveling over the playing surface of the apparatus may enter into the pockets with which the ball-stopping members are associated.

A further object of the invention is to provide a novel device for moving the ball-stopping members into ineffective position.

An additional object of the invention is to provide a novel device for controlling the number of said ball-stopping members which will be moved into ineffective or raised position at one time when the mechanism for moving the said ball-stopping members into ineffective or raised position is operated.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a top plan view of a game apparatus embodying a preferred form of the present invention;

Fig. 2 is a sectional view of the same on line 2—2 in Fig. 1;

Fig. 3 is a bottom plan view on line 3—3 in Fig. 2;

Fig. 4 is a vertical sectional view on line 4—4 in Fig. 2;

Fig. 5 is a bottom plan view of a device embodied in the invention for controlling the number of the ball-stopping members; which are moved into effective position at one time;

Fig. 6 is a sectional view on line 6—6 in Fig. 5;

Fig. 7 is a sectional view on line 7—7 in Fig. 5; and

Fig. 8 is a diagrammatic view of an electrical circuit embodied in the invention.

A game apparatus embodying a preferred form of the present invention is shown in the drawings, is therein generally indicated at 10, and comprises a cabinet 11 which includes an inclined playing board 12, and provided in the inclined playing board 12 are ball-receiving pockets 13. Slidably mounted in the cabinet 11, below the inclined playing board 12, is a ball-retaining member 14 and provided in this ball-retaining member are ball exit openings 15 which are adapted to be registered or aligned with the pockets 13 so as to discharge balls from the latter in a manner which is well understood in the art.

Mounted upon the inclined playing board 12, adjacent each of the ball-receiving pockets 13, is a supporting bracket 16 (Fig. 2) and pivotally mounted upon each of these supporting brackets 16, as at 17, is a ball-stopping member 18 which has, in the form of the invention shown, the shape or form of a spear, each of these ball-stopping members 18 being guided in, and the length of its movement determined by, a vertical slot 19 which is formed in an upright portion 20 of each of the brackets 16 (Fig. 2).

Attached to each of the ball-stopping members 18, at one end thereof, as at 21, (Fig. 2) is a link or small wire rod 22, and each of these links or small wire rods 22 depends, or projects downwardly, through an opening 23 which is formed in the inclined playing board 12.

Each of these links or small wire rods 22 is attached, at its lower end, as at 24, to an upright arm 25 of a latch member 29. Formed in each of the latch members 29 is an opening 28 and projecting downwardly through each of these openings 28 is the movable element or armature 26 of an electromagnet 27. Each of the latch members 29 is pivotally mounted, between its ends, as at 30, upon a supporting bracket 31 which is attached to the corresponding electromagnet 27, and each of the latch members 29 is urged (clockwise, Fig. 2) by a spring 32, while each of the movable elements or armatures 26 of the electromagnets 27 is urged (counterclockwise, Fig. 2) by a spring 33.

Formed in each of the latch members 29 is a latching finger or depressed portion 61 and each of these latching fingers 61 is latchingly engageable with a laterally extending flange 60 which

50

55

is formed on the corresponding member 26 (Fig. 2).

Attached to, and depending from, the slidable ball-retaining member 14, adjacent each of the latch members 29, is an arm 34, and each of these arms 34 has a cam or beveled edge 35 (Fig. 2), the purpose of which will be set forth herein-after.

Carried by the slidable ball-retaining member 14 (Fig. 5) is a plate or clip 36 and this plate or clip 36 is engageable with an end portion 37 of a slide bar 38 which is slidably mounted in the cabinet 11, on the bottom side of the inclined playing board 12, as shown in Fig. 5. Mounted 10 on the slide bar 38 is a pawl 39 and this pawl 39 is engageable with the teeth 40 of a ratchet 41 which is rotatably mounted, as at 42, upon the bottom side of the inclined playing board 12 (Fig. 6). Carried by, and depending from, the 15 ratchet 41 is a hub or shaft 43 and attached to this hub 43, at the lower end thereof, is a movable contact arm 44, and this movable contact arm 44 is successively engageable with a plurality 20 of stationary contacts 45—55—59 which are arranged in an annular row, (Fig. 6), these stationary contacts 45—55—59 being mounted upon a suitable support 46 in which the hub 43 is 25 loosely mounted (Fig. 6).

30 The electromagnets 27, stationary contacts 45 and 55, and the movable contact 44, are arranged in an electrical circuit which is generally indicated at 47 (Fig. 8), and likewise arranged in this circuit 47 is a suitable source of current 48 which may be, for example, a battery of dry 35 cells arranged in the cabinet 11; it being noted that the stationary contacts 59 are "blanks" that is, they are not electrically connected to any of the electromagnets 27.

Arranged in the circuit 47, adjacent each of the electromagnets 27, (Figs. 2 and 8) is a switch 49, and each of these switches 49 comprises a movable resilient contact 50, which is attached to, and is carried by, the corresponding latch member 29 (Fig. 2). Likewise embodied in each of the switches 49 is a stationary contact 51 with which the corresponding movable contact 50 is engageable, each of these stationary contacts 51 being mounted upon a supporting bracket 62 which is suspended from the inclined playing board 12 (Fig. 2) and these supporting brackets 62 also support the electromagnets 27.

Slidably mounted in an end wall 52 of the cabinet 11 is a ball-propelling device, in the form of a plunger 53, by means of which balls may be propelled onto the upper surface of the inclined playing board 12 so that they may gravitate there-over and enter into the pockets 13.

Likewise slidably mounted in the end wall 52 of the cabinet 11 is a coin slide 54.

Operation

The ball-stopping members 18 are normally disposed in ball-stopping or effective position, that is, in a plane substantially parallel to the plane of the inclined playing board 12, (as in full lines, Fig. 2), and when in this effective position a portion of each of the members 18 projects over, or above, the corresponding pocket 13 and thus prevents a ball 56 from entering pocket 13. However, when the slideable ball-retaining member 14 is shifted (left to right, Figs. 2 and 5) by the action of the coin slide 54, in a manner which is well understood in the art, the clip or plate 36 engages the end portion 37 of the slide bar 38, thereby moving the latter (left to right, Fig. 5,

against the action of the resetting spring 58 and thus moving the pawl 39 (left to right, Fig. 5), thereby moving the ratchet 41 and the movable contact 44 a predetermined circumferential distance (counterclockwise, Fig. 5), that is, a circumferential distance equal to the distance between two of the teeth 40 on the ratchet 41. When the movable contact arm 44 is thus moved (counterclockwise, Fig. 5), by the action of the pawl 39 and ratchet 41, it is moved out of engagement with the particular one of the stationary contacts 45—55—59 with which it is in contact and into engagement with the next succeeding stationary contact and, as shown by the arrangement of the contacts 45—55—59 in Fig. 8, the movable contact arm 44 may thus be moved into engagement with one of the stationary contacts 45 or into engagement with one of the stationary contacts 55, or into engagement with one of the stationary contacts 59, and in the event that the movable contact arm 44 engages one of the stationary contacts 45, it will then close the circuit 47 to the corresponding electromagnet 27 (Fig. 8), whereupon current will flow as follows: From one side of the source of current 48, through the conductor 63, into the hub 43, through the movable contact arm 44 and the particular stationary contact 45 with which the same is engaged, thence through the corresponding conductor 64 and switch 49 to one of the electromagnets 27, and thence by way of the corresponding conductor 65 back to the other side of the current source 48.

When the circuit 47 to one of the electromagnets 27 is thus closed, by the engagement of the movable contact arm 44 with one of the stationary contacts 45, the said electromagnet 47 which is thus actuated will attract its movable element or armature 26, (clockwise, from full to dotted line position, Fig. 2), against the action of its resetting spring 33, thereby moving the lower end portion of the member 26 to the left hand end of the slot 28 in the corresponding latch member 29, (as seen in Fig. 2), thus moving the flanged portion 60 of the member 26 out of latching engagement with the lip or depressed portion 61 of the corresponding latch, whereupon the spring 32 will pivot the latch member 29 (clockwise, from full to dotted line position, Fig. 2). This movement of the latch member 29 and its arm 25 pulls the link or small wire rod 22 downwardly in the corresponding slot 23, thereby pivoting the corresponding ball-stopping member 18 into ineffective position, (counterclockwise, from full to dotted line position, Fig. 2), and when the ball-stopping member 18 is in this ineffective position a ball 56 traveling over the inclined playing board 12 may enter into the pocket 13 with which the thus actuated ball-stopping member is associated.

The ball-stopping members 18 are retained in ineffective or dotted line position (Fig. 2) until the ball-retaining member 14 is moved (left to right, Fig. 2), by action of the coin slide 54, whereupon the beveled or angled edges 35 of the members 34 will engage the end portions 57 of the latch members 29 and thereby pivot the same, against the action of the springs 37 (counterclockwise, from dotted to full line position, Fig. 2). This movement of the latch members 29 acts, through the arms 25 of the same, to lift the small wire rods 22, thereby pivoting the ball-stopping members 18 back into effective or ball-stopping position (clockwise, from dotted to full line position, Fig. 2.) When the latch members 29

29 are thus moved, by the action of the members 34—35, back into effective position (as in full lines, Fig. 2) the springs 33 act upon the members 26 to pivot the latter (counterclockwise, 5 from dotted to full line position, Fig. 2), thereby moving the flanged portions 60 of the members 26 under the depressed portions 61 of the members 29, and thereby latchingly engaging the latch members 29 and the movable elements 26 10 of the electromagnets 27.

During the foregoing movement of the latch member 29, the contact 50 carried thereby engages the contact 51, thus closing the corresponding switch 49 and thereby pre-disposing 15 the circuit 47 in condition to be closed when the coin slide 54 and ball-retaining member 14 are again operated (left to right, Fig. 2).

It will be noted, by reference to Fig. 8, that the annular row of stationary contacts therein 20 shown includes the contacts 55 which, when engaged by the movable contact 44, do not energize any of the electromagnets 27 and hence do not actuate any of the ball-stopping members 18.

25 It will also be noted that the annular row of stationary contacts in the control device (Fig. 7) includes the contacts 55, each of these contacts 55 being electrically connected, by a branch conductor 66, to a common conductor 67 and this conductor 67 leads to one side of the switch 49 which has associated therewith the particular electromagnet 27 which is designated "A", Fig. 8; the other side of the electromagnet 27 "A" being electrically connected to the current 30 source 48 by means of conductors 68 and 71.

35 Leading from the conductor 67 to one side of the switch 49 which is associated with the electromagnet 27 "B" is a conductor 69, and the other side of the electromagnet 27 "B" is electrically connected, by way of the conductors 70 and 71, to the current source 48.

Accordingly, when the movable contact 44 engages one of the stationary contacts 55 both of the electromagnets 27 "A" and 27 "B" will be 40 energized and hence will raise or lift the corresponding ball-stopping members 18 into raised or ineffective position, current then flowing as follows: From one side of the current source 48, through the conductor 63 to the hub 43, through 45 the movable contact arm 44, through the particular stationary contact 55 with which the movable contact arm 44 is in engagement, thence by way of the corresponding conductor 66, and conductor 67 to the switch 49 which is associated 50 with the electromagnet 27 "A", through the latter, thence by way of the conductors 68 and 71 back to the other side of the current source 48, thus energizing the electromagnet 27 "A" and raising the corresponding ball-stopping 55 member 18 into ineffective position, and at the same time, current will also flow from the conductor 67, by way of the conductor 69, into the switch 49 which is associated with electromagnet 27 "B", through the latter, and thence back 60 into the current source 48 by way of the conductor 70 and 71; it being thus noted that when the movable contact 44 is disposed in engagement with one of the stationary contacts 55 a predetermined number of the electromagnets 27 65 (that is, in the present instance, two of the electromagnets, 27 "A" and 27 "B") are energized and a corresponding number of the ball-stopping members 18 are moved into ineffective position, it being understood that more than two electromagnets 27 may be energized at one time, if 70

so desired, by the engagement of the movable contact 44 with one of the stationary contacts 55, the number not being limited to two, as in the wiring diagram shown in Fig. 7, since this wiring scheme may be varied to the end that 5 three or more electromagnets 27 may be simultaneously energized by the engagement of the movable contact 44 with one of the stationary contacts 55.

The switches 49 in circuit with each of the electromagnets 27 are operable to interrupt the flow of current through the windings thereof after any one of them has been energized by a circuit set up by the commutator switch. In other words, as soon as any one of the magnets is 15 energized to release its latch mechanism, the individual switch 49 thereof will open, interrupting the energizing current. This is necessary obviously to conserve power, since the commutator switch is not thereafter operated until 20 the shuffle panel is again moved.

While I have illustrated and described the preferred form of construction for carrying my invention into effect, this is capable of variation and modification, without departing from the 25 spirit of the invention. I, therefore, do not wish to be limited to the precise details of construction set forth, but desire to avail myself of such variations and modifications as come within the scope of the appended claims. 30

Having thus described my invention, what I claim as new and desire to protect by Letters Patent is:

1. In a game apparatus, a cabinet including a member providing a ball-playing surface provided 35 with ball-receiving pockets, a ball-stopping member movably mounted upon said playing surface adjacent each of said pockets and each of said ball-stopping members having a portion normally projecting over and above the corresponding 40 one of said pockets so as to prevent balls traveling over the said playing surface from entering the said pockets, means for moving the said ball-stopping members in a direction to move the said portions thereof away from said 45 pockets into ineffective position so as to allow balls traveling over said playing surface to enter into the said pockets, and means for controlling the number of said ball-stopping members which are moved into ineffective position at one time 50 by the action of said first-named or moving means.

2. In a game apparatus, a cabinet including a member providing a ball-playing surface provided with ball-receiving pockets; a plurality of 55 ball-stopping members mounted for movement in a direction substantially normal to said surface upon said playing surface and each having a portion normally projecting over or above one of said ball-receiving pockets so as to prevent balls traveling over the said playing surface from entering the said pockets, means for moving the said ball-stopping members into ineffective position and the said portions thereof away from their normal or effective position above said 60 pockets so as to allow balls traveling over said playing surface to enter the said pockets, and means for controlling the number of said ball-stopping members which will be moved into ineffective position by said first-named or moving 65 means at each operation of the latter.

3. In a game apparatus, a cabinet including a member providing a ball-playing surface provided with ball-receiving pockets; a plurality of ball-stopping members pivotally mounted upon 70

said playing surface and each having a portion normally projecting over or above one of said ball-receiving pockets so as to prevent balls traveling over said playing surface from entering 5 the said pocket, means for pivoting the said ball-stopping members into ineffective position and the said portions thereof upwardly away from said playing surface and away from their normal or effective position above said pockets so as to 10 allow balls traveling over said playing surface to enter the said pockets, and means for controlling the number of said ball-stopping members which will be pivoted into ineffective position by said first-named or pivoting means at 15 each operation of the latter.

4. In a game apparatus of the type having an inclined ball-playing board with ball-receiving apertures therein and a shuffle member movable below said apertures to permit balls to pass 20 therethrough, control means comprising ball-

stopping members pivotally mounted on said board and each having an end portion normally projecting over one of said ball-receiving apertures therein to prevent a ball from entering said aperture, said stopping members being releasable for pivotal movement to move their respective said end portions into ineffective ball-stopping position relative to their respective said apertures, means urging said stopping members into ineffective position, means operable by said 10 shuffle member and including a rotatable switching device and electromagnetic means controlled thereby for releasing selected ones of said ball stopping members for pivotal movement into ineffective ball-stopping position, and means also 15 operable by said shuffle member for resetting ball-stopping members from pivoted, ineffective position to effective ball-stopping position.

DAVID C. ROCKOLA. 20
